US00D500799S

(12) **United States Design Patent** (10) Patent No.: **US D500,799 S**
(45) Date of Patent: **** Jan. 11, 2005**

(54) **ELECTRICAL PROBE**

(75) Inventor: **Geoffrey Olson**, Round Lake, IL (US)

(73) Assignee: **Greenlee Textron Inc.**, Rockford, IL (US)

(**) Term: **14 Years**

(21) Appl. No.: **29/186,476**

(22) Filed: **Jul. 16, 2003**

(51) LOC (7) Cl. **10-04**

(52) U.S. Cl. **D19/80**

(58) Field of Search **D10/80, 78; 324/22.5, 324/133, 149, 158, 501, 519, 527, 530, 555, 556**

(57) **CLAIM**

The ornamental design for an electrical probe, as shown and described.

DESCRIPTION

FIG. 1 is a perspective view of the electrical probe according to my design;

FIG. 2 is a right side elevational view of the electrical probe;

FIG. 3 is a top plan view of the electrical probe;

FIG. 4 is a left side elevational view of the electrical probe;

FIG. 5 is a bottom plan view of the electrical probe;

FIG. 6 is a front elevational view of the electrical probe; and,

FIG. 7 is a rear elevational view of the electrical probe.
